D535,808 S	1/2007	Beland

DESCRIPTION

FIG. 1 is a front perspective view of a shirt showing our new design;

FIG. 2 is an opposite side front perspective view thereof;
FIG. 3 is a rear perspective view thereof;

FIG. 4 is an opposite side rear perspective view thereof;

FIG. 5 is a front view thereof;

FIG. 6 is a rear view thereof;

FIG. 7 is a side view thereof; and,

FIG. 8 is an opposite side view thereof.

The broken lines depicting the remainder of the shirt form no part of the claimed design.

1 Claim, 8 Drawing Sheets
